UNITED STATES PATENT OFFICE.

THEODORE BOSSHARD, OF BROOKLYN, NEW YORK.

CHERRY AND CONFECTION CENTER DEPOSITING APPARATUS.

Application filed June 9, 1922. Serial No. 567,217.

To all whom it may concern:

Be it known that I, THEODORE BOSSHARD, a citizen of the United States, and resident of the city of New York, borough of Brooklyn, county of Kings, and State of New York, have invented a new and Improved Cherry and Confection Center Depositing Apparatus, of which the following is a full, clear, and exact description.

10 My invention relates to a confectionery apparatus and has particular reference to a device for depositing confections.

It is an object of the present invention to provide a confectionery apparatus in 15 the nature of a depositor by means of which a number of operators may be dispensed with and which is particularly applicable for laying cherries, nuts, etc., on molded starch boards, and which apparatus will be 20 extremely simple in construction, and further be capable of being placed upon the market at a nominal figure, aside from the fact that its simplicity of construction will insure a long life and a freedom from mechanical defects.

A further object of my invention is that of providing an improved construction in which the articles being deposited may first be more readily moved to a position upon 30 the tray, and secondly and subsequently be more efficaciously distributed upon a starch board.

With these and further objects in mind the present invention includes essentially a 35 receptacle within which a tray is positioned together with means whereby the articles to be distributed upon the tray may be caused to move upon the same, the said tray also embracing an improved construction, in that means are provided insuring a 40 correct depositing of the articles placed thereon.

In the attached drawings one practical embodiment of my invention has been 45 shown, and it will be seen in these views that;

Figure 1 is a plan view of the said apparatus.

Figure 2 is a sectional side view taken 50 along the line 2—2 and in the direction of the arrows indicated in Figure 1.

Figure 3 is a transverse sectional view taken along the line 3—3 and in the direction of the arrows also indicated in Figure 1.

Figure 4 is a bottom plan view of the tray, and

Figure 5 is a perspective view of the trough which co-operates with the said tray.

It will be seen in these various views that the reference numeral 11 indicates the receptacle which is preferably cradle-shaped and within which there is disposed a tray, the same including a body and supporting legs 12 therefor, which supporting legs bear against the inner lower face of the receptacle 11 and are preferably shaped to conform to the contour of this face.

Referring to the construction of the tray 70 it will be seen that the reference numeral 13 indicates the body of the tray which is formed with a series of transversely extending grooves 14 in its upper face, these grooves being each interrupted by a series 75 of openings 15. It is noted that the body 13 has one of its longitudinal edges preferably bearing against the inner face of the cradle 11, but its opposite edge portion is so arranged as to be in spaced relation- 80 ship to the said receptacle for a purpose hereinafter specified. Also a sliding plate 16 forms the bottom of the tray and normally closes the openings 15. A move- 85 ment of the plate with respect to the body 13 may be effected by a lever 17. I prefer to employ slots 18 in the said plate 16, these slots being adapted when the plate is moved with respect to the body of the tray, to each be brought into alignment with one 90 of the rows of perforations 15 in the body 13 of the tray to deposit the cherries resting therein.

I have found that by adopting this construction the articles retained within the 95 openings 15 may be deposited in a more convenient and efficient manner, and aside from the foregoing the plate 16, which may be of slate, may be more economically constructed, and the parts of the tray may be 100 cleaned in a better manner.

Now with a view of distributing the articles to be deposited on to the upper face of the tray, it will be noted that I conveniently utilize a receptacle 19 presenting a 105 trough shape, and this receptacle is rockingly supported within the apparatus, and at a point above the tray by the use of a pair of arms 20, which are attached to the legs 12, and extend upwardly therefrom, the upper 110

ends of these arms being preferably notched as in Figure 3, so that a rocking detachable support between the trough 19 and the remainder of the apparatus is effected by the 5 association of pins 21 with the ends of the trough, which pins engage the notched upper end portions of the arms 20, it being further noted that hand grip portions 22 may be provided in the ends of the trough 10 so as to permit an operator to remove the same from the apparatus.

In use, the receptacle 11 is placed upon a suitable supporting surface, and the trough 19 is filled with cherries or the other articles 15 which are to be deposited. It will be found that upon the parts being in the position shown in Figures 1 to 3, and the trough 19 having been filled that the latter may be tilted so as to release not alone sufficient 20 articles to fill all of the openings 15 of the tray, but also a surplusage of articles. It will be found subsequently that by merely rocking the cradle 11 to and fro a number of times that all of the articles thus placed 25 upon its upper surface will be efficiently distributed over the face of the tray so that one article fills each opening or space 15.

As has been shown in Figures 2 and 4, the tray is detachably associated with the legs 30 12 although when the same is in position any movement between these parts is prevented incident to the provision of ledge portions 23 which are associated with the tray. Thus upon the tray being filled the 35 same is lifted clear of the legs 12, and at an angle to the body of the apparatus so that the surplusage of articles upon the upper face of the tray will fall into the cradle 11 from which they may be subsequently removed when desired.

The tray is now placed in position over the molded starch board and the contents of the same are removed by simply moving the plate 16 with respect to the body of the tray 45 whereby to bring the slots 18 thereof into alignment with the series of openings 15 of the body 13. The articles will then assume a position upon the starch board and this position will be correct in all respects so that the said board may pass under the 50 cream casting machine in the usual way.

It will also be noted that during the movement of the cradle 11 the trough member 19, incident to its method of mounting will 55 remain in a position at which it will not spill its contents and if an operator finds it necessary to remove said member this may readily be accomplished by simply lifting the same clear of the arms 20.

60 Thus it will be understood that the objects of this invention have been accomplished it being of course understood that the apparatus herewith shown and described may be utilized for any desirable purpose, and it 65 will be noted in connection with the ledge

portions 23 that the same provide a structure which has its parts angularly disposed with respect to each other. Thus although the tray is normally immovable with respect to the cradle the same may readily be detached therefrom when an operator so desires, and it will finally be appreciated that numerous modifications of structure might readily be resorted to without in the least departing from the scope of my claims; 70 which are—

1. An apparatus for the depositing of cherry and other confection centers including a receptacle, a tray positioned within said receptacle and having a plurality of 80 openings therein for receiving cherries and the like, said tray also having one of its edges spaced from the inner face thereof, and means adjacent said edge from which articles are deposited onto said tray. 85

2. An apparatus for the depositing of cherry and other confection centers including a receptacle, a tray positioned within said receptacle and having a plurality of 90 openings therein for receiving cherries and the like, said tray also having one of its edges spaced from an adjacent wall thereof, and an article holder pivotally mounted in said receptacle at a point contiguous to the space between said edge of the tray and wall 95 of the receptacle and from which articles are deposited onto said tray.

3. An apparatus for the depositing of cherry and other confection centers, comprising a receptacle, a tray removably supported in said receptacle and spaced from the bottom thereof, said tray being provided with a series of troughs having a plurality of openings therein, a movable bottom for said tray having a series of slots therein 105 normally out of alignment with said openings to prevent articles from passing through said openings, means for moving said bottom to align said slots and openings, and an article holder pivotally supported 110 within said receptacle above said tray.

4. An apparatus for the depositing of cherry and other confection centers, comprising a receptacle, an article holder pivotally supported within said receptacle, and a tray removably mounted within said receptacle below said article holder and provided with a plurality of recesses adapted to receive articles from said holder whereby the same are evenly distributed over said tray. 115

5. An apparatus for the depositing of cherry and other confection centers, comprising a receptacle, an article holder pivotally supported within said receptacle, a tray removably mounted within said receptacle 125 below said article holder and provided with a plurality of recesses adapted to receive articles from said holder whereby the same are evenly distributed over said tray, and means for removing said articles from said 130

tray and depositing said articles in the same relative positions that they assumed within the tray.

6. An apparatus for the depositing of cherry and other confection centers, comprising a receptacle, supporting members extending transversely of said receptacle and engaging the walls thereof, a tray with-

in said receptacle and removably mounted on said supporting members, one side of ¹⁰ said tray being spaced from the adjacent wall of said receptacle, and an article holder pivotally mounted within said receptacle and positioned above said tray and the space formed between it and said wall.

THEODORE BOSSHARD.
